UNITED STATES PATENT OFFICE

2,449,362

EXPLOSION-PROOF LAMP

James R. Bell, La Grange, Ill., L. David Stacy, Burk Burnett, Tex., and Irvin E. Dischinger, Jr., Berwyn, Ill., assignors to General Motors Corporation, Detroit, Mich., a corporation of Delaware

Application March 25, 1947, Serial No. 737,122

3 Claims. (Cl. 240—11.2)

1

The present invention relates to lamps and more particularly to lamps of the explosion proof type.

The principal object of the present invention is to provide a portable explosion proof lamp housing including a lens, electric lamp, and means to prevent illumination of the lamp unless there is pressure flow through the housing in order to properly cool the parts and pressure flow out of openings in the housing adjacent the exterior of the lens to reduce contamination of the exterior of the lens by particles in the surrounding atmosphere.

Figure 1 of the drawing is a longitudinal cross sectional elevation of the lamp structure.

Figures 2 and 3 are views taken on lines 2—2 and 3—3 of Figure 1, respectively, with parts broken away and in section.

As best shown in Figure 1 the lamp housing comprises two symmetrical pistol grip portions 1 each having an internal semicircular groove 3 in which a circular gasket 5 and the exterior circular flanged inner end portion 7 of a housing member 9 in the form of a frustum of a cone is clamped by means of machine screws, not shown, and clamping bolts and nuts 11, shown in Figure 3, extending through openings in the pistol grip portions 1. An annular lens support 13 having an externally flanged outer end portion 15 is snugly secured in the outer end of the housing 9 by machine screws 17 and to the inner face of the externally flanged inner end portion 21 of the support 13 a gasket 23 and a lens 25 is clamped by a split retaining ring 27 of semicircular section having a clamping means 29 shown between the ends of the ring 27 to provide this clamping force. A plurality of circumferentially spaced pressure outlet openings 31 are provided in the lens support member 13 between the flanged end portions 15—21 as shown in Figures 1 and 2. The axes of these openings extend in the direction of the arrows shown in Figure 1 and intersect the axis of the annular lens support 13 at a point exterior to the lens to displace any particles in the atmosphere outside the lens surface away from this surface to reduce contamination of this surface.

An incandescent electric flood lamp 33 is supported in an insulated electrical socket member 35 secured by nuts 37 to one pistol grip member 1 in coaxial relation to the lens 25. The socket member 35 is provided with openings 39—40, as best illustrated in Figures 1 and 3, for passage of fluid pressure from the interior of the pistol grip members 1 to the interior of the housing 9 and outwardly through the outlet openings 31 in the lens supporting member 13 for the purpose described.

2

Pressure from a suitable source, such as an outlet valve, not shown, on an operator's helmet is applied through a flexible hose 41 shown connected at one end by threaded connections 43 to the inlet of a pressure flow switch 45 in the outer end of the pistol grip members 1. The flow switch 45 is a conventional member having normally opened electrical switch contacts and a member, not shown, responsive to flow of pressure through the switch and outwardly through an outlet opening 47 to cause closure of the switch contacts. A rubber covered three conductor cable 49 is also clamped between facing semicircular grooved portions in the end of the pistol grip members 1. One cable conductor 51 is grounded in one pistol grip member 1 and the outer end is connected to ground. A second cable conductor 53 is connected to one terminal of the lamp socket member 35 and the remaining cable conductor 55 is connected to one terminal and contact of the pressure flow switch 45. A finger operated trigger switch 57 of conventional type and having normally open contacts, not shown, which are closed upon depression of the trigger member 59 is secured snugly between the pistol grip members and the separate contacts and terminals thereon are shown connected by conductors 61—63 in series between the other terminal of the lamp 33 and other terminal of the flow switch 45.

It will be evident that with the outer ends of the cable conductors 53—55 connected across an electrical source and the pressure flow switch 45, trigger switch 57 and lamp 33 connected in series relation therebetween by conductors 61—63 the lamp circuit can only be completed to cause illumination of the lamp by closure of the pressure flow switch at a proper rate of pressure flow which causes circulation of fluid pressure through the interior of the pistol grip members 1, openings 39—40 in the socket, around the lamp 33 in the housing 9 and outwardly through the outlet openings 31 in the lens support member to prevent contamination of the outer face lens. Fluid flow in the lamp housing at greater pressure than the surrounding atmosphere tends to prevent entrance of atmosphere into the lamp housing and if the switches 45—59 are non-arc type in which the contacts are sealed in a tube filled with mercury which is tipped to connect the contacts upon pressure flow and by the trigger there is little danger of causing an explosion by use of this lamp structure even if the lamp bulb breaks. The parts of the lamp are cooled to a safe temperature in the surrounding atmosphere and long life of the lamp bulb is obtained and infrequent

cleaning of the lens is necessary. By the use of light metal parts in the lamp housing and attaching the pressure hose to the operator's helmet the operator may easily enter and leave small openings and work in confined spaces with adequate illumination without danger of electric shock or explosion.

We claim:

1. A portable light source comprising an incandescent electric lamp, a lamp housing including a lens adjacent said lamp, pressure outlet openings for directing pressure flow outwardly away from said lens, a pressure inlet connection adapted to be connected to a source of fluid pressure, an electric switch adapted to be closed by flow of pressure therethrough and connected to said pressure inlet connection and a manually operable electric lamp switch operable to a closed position from outside said housing, and a power cable extending through an opening in said housing for connecting said lamp and switches in series with an electrical power source.

2. A portable light source comprising an incandescent electric flood lamp, a lamp housing including a sealed lens adjacent said lamp, pressure outlet openings adjacent the periphery of said lens for directing pressure flow outwardly of said housing to a point on the axis of said lens, a pistol grip housing portion including a pressure inlet connection adapted to be connected to a source of fluid pressure, an electric switch connected to said pressure source and adapted to be closed by flow of pressure through said housing, a trigger closed electric switch and an electric cable extending snugly through an opening in

4
said pistol grip housing portion for connecting said lamp and switches in series with an electrical source.

3. A portable light source comprising an incandescent electric flood lamp, a lightweight lamp housing having end openings, a lens sealed in one opening, said housing having circumferentially spaced pressure outlet openings adjacent said lens for directing fluid pressure flow outwardly of said housing toward a point on the axis of said lens, a hollow pistol grip clamped in fluid tight relation with said other lamp housing opening and including a trigger closed electric switch and a second electric switch adapted to be closed by pressure flow therethrough, said pistol grip including a fluid pressure inlet connection connected to said flow switch and a flexible electrical cable extending snugly through an opening in said pistol grip for connecting said lamp and said electric switches in series circuit relation across a source of electrical power.
